DESIGN FOR A BAG FOR HATS OR SIMILAR ARTICLES

Application filed July 8, 1931. Serial No. 40,466. Term of patent 7 years.

To all whom it may concern:

Be it known that I, SARA PEIRCE WHITE JOHNSTONE, a citizen of the United States, residing at Boston, in the county of Suffolk and State of Massachusetts, have invented a new, original, and ornamental Design for a Bag for Hats or Similar Articles, of which the following is a specification, reference being had to the accompanying drawings, forming a part thereof, in which

Figure 1 is a perspective view, Figure 2 is a side elevation, and Figure 3 is a plan view of my bag for hats.

Said bag consists of a bottom 5, sides 6 surrounded by a narrow border 7, flaps 8 which loosely extend beyond said sides 6 and have a border 9 extending along their outside edges. Strings 10 attached to said sides 6 are adapted to draw said sides together thereby closing the bag.

I claim:

The ornamental design for a bag for hats or similar articles as shown and described.

SARA PEIRCE WHITE JOHNSTONE.
